ttorney
Pierre Barnes

UNITED STATES PATENT OFFICE.

JAMES O. ANDERSON, OF EUGENE, OREGON.

DRAFT-REGULATOR.

1,341,872.

Specification of Letters Patent. Patented June 1, 1920.

Application filed October 8, 1919. Serial No. 329,395.

To all whom it may concern:

Be it known that I, JAMES O. ANDERSON, a citizen of the United States, residing at Eugene, in the county of Lane and State of Oregon, have invented certain new and useful Improvements in Draft-Regulators, of which the following is a specification.

This invention relates to draft regulating devices and is adapted, more especially, for controlling chimney gases from retorts or smelting furnaces although it may advantageously be used in other applications.

The objects of the invention are, first, to provide an efficient chimney damper where-
15 in is employed water for the draft regulat-
ing medium; and, second, the provision of
means which will serve automatically to
regulate such liquid damper for the pur-
pose of affording a substantially uniform
20 flue opening under normal operating condi-
tions.

A further object is to provide damper de-
vices of this character which may be inex-
pensively installed and be reliable and ef-
25 fective in operation.

These objects are accomplished by means
of apparatus which will be hereinafter de-
scribed and claimed.

In the accompanying drawings, Figure
30 1 is a side elevational view, partly in ver-
tical section, showing an embodiment of my
invention. Figs. 2 and 3 are sectional de-
tail views, to an enlarged scale, of the auto-
matic water-level regulating valve, shown
35 in different positions.

In said drawings, the reference numeral
5 designates a retort or other vessel from
which gaseous products are discharged
through a stack or flue, indicated as a whole
40 by 6. Said flue is shown in Fig. 1 with an
inclined central portion, an upper portion
8 of a substantially semicircular form and
terminates in a downwardly directed outlet
end 9 which is disposed in a horizontal
45 plane, or nearly so.

Such curved extremity of the flue extends
into a tank 10 which constitutes with the
above described flue the gas or smoke stack.

Said tank is of greater diameter than the
50 flue, is open at the top and is desirably pro-
vided with a funnel shaped bottom 11 con-

nected at its lowest part with a sediment
collecting pipe 12 provided with a draw-off
cock 13.

The tank 10 has connected thereto a serv-
ice pipe line 14 leading from a source of
water supply. Included in said pipe line
for shutting off the water supply is a valve
15 and between the latter and the tank is a
valve 15¹ by which water may be drawn 55
from the tank. 16—16¹ represents a by-pass
connection between the pipe line at opposite
sides of the two valves, and is provided with
a manually controlled shut-off valve 17 and
also with a three-way valve, denoted gener-
ally by 18. This three-way valve, as shown
in Figs. 2 and 3, consists of a valve proper
19 rotatable in the bore of a casing 20 hav-
ing at diametrically opposite sides connec-
tions with the by-pass parts 16 and 16¹ and 60
at right angles therewith an outlet connect-
ed to a waste pipe 21. The valve 19 is pro-
vided, as shown, with a T-shaped passage
19¹ which by suitably rotating the valve
opens communication, as in Fig. 3, for the 65
passage of water through the by-pass and
pipe line into tank 10; or into position (Fig.
2) to afford an outlet for the water from
the tank. The valve 19 is provided with a
lever handle 22 which, as shown in Fig. 1, 70
is engageable by attachments 23 or 23¹ upon
a cable 24 guided by pulleys 25 and connect-
ed to a sheave 26 which is located above said
tank. 75

Instead of using cable attachments as re-
ferred to above, the cable 24 may be con-
nected, as in Figs. 2 and 3, directly to a le-
ver arm 22¹ by which the valve 19 is oper-
ated, and employing a counter weight 30 on
the other arm of the lever to act in opposi-
tion to the weight of a body 28 hereinafter
referred to. A second cable 27 wound about
the sheave axle 26¹ is connected to body 28
which floats in the water W obtaining in
the tank so that when the water descends 90
the weight of the body 28 will act in an ob-
vious manner to rotate the valve 19 into a
position as shown in Fig. 3 to admit water
into the tank. As the body 28 ascends with
the rising of water in the tank, a pendent 95
weight 29, Fig. 1, upon cable 26, or a coun-
ter weight 30 in Figs. 2 and 3, asserts its
100

power to effect the closing of the valve 19 to stop the flow of water when it reaches a predetermined level suitable for normal operations.

5 The valve 19 by being operable through the instrumentality of a body floating in the liquid-damper will be responsive to changes in the level of the water, and which may be regulated relative to the plane of the flue outlet end 9 by regulating the connection between the cable 24 and valve 19.

The water level in the tank may also be manually controlled, after shutting off valve 17, by means of valves 14 and 15 as, for example, for lowering the water level when starting operations by affording more space between the flue outlet and the water for the purpose of increasing draft; or, where the draft is to be lessened or entirely overcome, 10 the water level should be raised into proximity of or to be in contact with the flue outlet.

To enable the apparatus being again automatically regulated, the valves 14 and 15 are closed and the valve 17 opened, whereupon the three-way valve becomes operative and is caused to be brought into Figs. 2 or 3 positions according to whether the water within the tank is above or below the level 30 for which the automatic devices are regulated.

While I have illustrated in Figs. 2 and 3 full open positions of the valve 19, it is to be noted that the valve will, under ordinary 35 conditions, be barely open or closed at any time.

31 represents a register of any suitable or well known type whose pointer is actuated by means of cable 24 to indicate the level of 40 the water within the tank.

In operation, the gaseous products of combustion or which result from the roasting or smelting of metallic ores or the like are caused by a natural draft or otherwise 45 to ascend through the flue 6 to escape through the discharge end 9 into the external atmosphere.

By increasing or diminishing the effective opening of such discharge end or more particularly in this instance the opening under the periphery of the discharge end, it is apparent that the draft will respectively be increased to its maximum extent which will occur when the level of the water W is at a 55 distance equal to one fourth of the diameter of said discharge end, and the draft will be lessened to nothing by raising of the water level to the discharge end of the flue.

By my improved means for governing the 60 elevation of the level of the water damper I produce apparatus capable of regulating the draft to a very fine degree.

This function of the invention is peculiarly valuable in metallurgy for the recovery 65 of mercury or the like from gases or

volatile particles which are separated from other material in the ore.

For which purpose the use of the inclined flue 6 with a discharge extremity of an inverted U-shape which directs the gases, etc., 70 against a water surface and affords effective means to save nearly all of the "values" which hitherto it has been impossible to retain in vertical flues from which escape the gaseous products at a high temperature. 75

The construction, operation and advantages of my invention will, it is thought, be apparent from the foregoing description.

What I claim is—

1. In an apparatus of the class described, 80 the combination of a water container, a flue having at its upper end a return bend which extends into said container, means to supply water into said container to predetermined elevations and with respect to the discharge 85 extremity of the flue bend whereby the draft in the flue may be regulated.

2. In apparatus of the class described, a water container, a flue having a downwardly directed outlet end extending into 90 said container, a pipe for supplying water into and withdrawing the same from the container, said pipe being connected with a source of water supply, a three-way valve included in said pipe, said valve having a 95 waste outlet, and means actuated by the water level in said container for operating said valve to regulate the level of the water in said container with respect to the flue outlet. 100

3. In apparatus of the class described, a water container, a flue having its outlet extend downwardly into said container, a single pipe line connected to said container, valves provided in said pipe line whereby 105 water is supplied to and withdrawn from said container to cause the water level therein to be at a selected elevation for varying the effective opening of the flue outlet, and means regulated by the elevation of the 110 water level in said container whereby the water level is automatically retained at a distance from the flue outlet to maintain a substantially uniform draft opening thereat.

4. In apparatus of the class described, the 115 combination of an inclined flue having its discharge end of an inverted U-shape with a downwardly directed extremity, a water container into which said flue end extends, said container being of greater diameter than 120 said flue discharge, means for admitting water into and discharging the same from said container and devices actuated by changes of the elevation of the water level in said container for regulating said means. 125

5. In apparatus of the class described, a water container having a sloping bottom, a sediment collecting vessel connected thereto, a valve outlet therefor, a flue having an inclined portion and an outlet portion, said 130

outlet portion extending into said container and having its discharge extremity located a short distance above the bottom of said container, means for supplying water to said container, and means to withdraw water from the container through the aforesaid means or said vessel selectively.

Signed at Seattle, Washington, this 1st day of October, 1919.

JAMES O. ANDERSON.
